Attorney

UNITED STATES PATENT OFFICE.

RIVES FLEMING, OF RICHMOND, VIRGINIA.

CANE.

Application filed April 9, 1926. Serial No. 100,952.

This invention relates to canes, more specifically to canes capable of being used as a means of defense.

The object of this cane is to provide the user with a cane or walking stick which at a moment's notice may be turned into a formidable means of defense.

The novelty of the cane lies chiefly in mounting a blade in a cane in such a manner, that the cane can quickly be transferred into a weapon of defense.

Further novelty lies in the manner of projecting the blade from the cane.

Still other novelty lies in the handle acting as a weight to direct the point of the blade.

In the drawings:

Fig. 1 is a full length perspective of the cane,

Fig. 2 is a perspective of the cane with a portion of its length removed showing the knife blade in open position, and

Fig. 3 is a vertical section showing the means for operating the blade.

As shown in Fig. 1, the blade 1 is safely encased in cane 2 and is controlled by a button 3 mounted in slot 4.

In Fig. 2 is shown a blade 1 in open position from slot 5 and in alinement with handle 5.

In Fig. 3 is shown the blade 1 encased in cane 2, with a spring 6 resting against the face of blade 1, a locking member 3 in engagement with indent 8 in blade 1, a pivotal member 9 on which the blade 1 operates.

As actually used the cane presents all the appearances of the usual walking stick. In case of attack the user may by pressing button 3 release the blade which, because of spring 6, will spring into open position as shown in Fig. 2. The cane can then be

grasped near the bottom and used in the manner of a tomahawk.

What I claim is:

1. A combination of a cane having a handle at right angles to the body thereof, a blade pivoted at the joint of the handle and the body of the cane, said blade adapted to be closed into the body of the cane and opened into alinement with the handle of the cane.

2. A combination of a cane having a handle at right angles to the body thereof, a blade pivoted at the joint of the handle and the body of the cane, a spring positioned in the cane, said spring resting against the face of the blade to force the blade into an open position, a locking means, the locking means consisting of an indent in the blade and a bar, said bar capable of being moved into or out of engagement with the indent.

3. A combination of a cane having a handle at right angles to the body thereof, a blade pivoted at the joint of the handle and the body of the cane, a spring positioned in the cane, said spring resting against the face of the blade to force the blade into an open position, in alinement with the handle of the cane, said handle acting as a weight to direct the point of the blade.

4. A combination of a cane having a handle at right angles to the body thereof, a blade pivoted at the joint of the handle and the body of the cane, said blade adapted to be closed into the body of the cane and opened into alinement with the handle of the cane and on the side of the cane opposite the handle, said handle of the cane acting as a weight to direct the point of the blade.

In testimony whereof I affix my signature.

RIVES FLEMING.
